UNITED STATES PATENT OFFICE.

JAY Y. WILKINS, OF KEW GARDENS, NEW YORK, ASSIGNOR TO M. ASCHER SILK CORPORATION, A CORPORATION OF NEW YORK.

DESIGN FOR A TEXTILE FABRIC.

Application filed October 11, 1922. Serial No. 3,938. Term of patent 3½ years.

To all whom it may concern:

Be it known that I, JAY Y. WILKINS, a citizen of the United States of America, and resident of the town of Kew Gardens, county of Queens, and State of New York, have invented a new, original, and ornamental Design for a Textile Fabric, of which the following is a specification, reference being had to the accompanying drawing, forming part thereof.

The figure is a plan view of a textile fabric, illustrating my new and ornamental design.

I claim:

The ornamental design for a textile fabric as shown.

JAY Y. WILKINS.

Witnesses:

IRVING ROSEN,
E. DE URIARLE.
